Primary Examiner — Cynthia M Chin

(57) **CLAIM**

I claim the ornamental design for a scooter, as shown and described.

DESCRIPTION

FIG. 1 is a front elevational view of a scooter showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a perspective view thereof.

The broken line portions of the drawings depict environmental structure that forms no part of the claimed design.
